PRINTING PRESS MARGIN BAR

Henry A. Wise Wood, New York, N. Y., assignor
to Wood Newspaper Machinery Corporation,
New York, N. Y., a corporation of Virginia

Application October 4, 1932, Serial No. 636,099
Renewed December 6, 1934

5 Claims. (Cl. 101—378)

This invention relates to that type of means for holding down printing plates on their cylinders which act along the straight sides of the plates.

The principal object of the invention is to provide a means for clamping a plate along its straight sides in which the clamping means is made movable in an axial direction with respect to the plate, so that the plate may be removed more easily than heretofore, and so that any inaccuracies in the plate may easily be accommodated by the movable margin bar, and to provide surfaces in the plate cylinder cooperating with the margin bar of such a nature that when one end clamp has been opened all the margin bars affecting the plates clamped by that clamp are moved longitudinally on an incline to relieve the pressure of the margin bars against the ledges carried by the plate and the closing of the end clamp will lower the side clamps and lock the plates.

Other objects and advantages of the invention will appear hereinafter.

Reference is to be had to the accompanying drawings, in which

Fig. 1 is a plan of a plate clamping means constructed in accordance with this invention and applied to a typical plate cylinder;

Fig. 2 is a longitudinal sectional view on the line 2—2 of Fig. 1, showing the position of the parts with the plates clamped;

Fig. 3 is a similar view showing the position of the parts with the plates unclamped;

Fig. 4 is a sectional view on the line 4—4 of Fig. 2;

Fig. 5 is a sectional view on the line 5—5 of Fig. 3;

Fig. 6 is a plan of one of the margin bars, as shown in Fig. 4, and

Fig. 7 is a sectional view as indicated by the line 7 in Fig. 6.

The invention is shown as being applied to a plate cylinder 1 having the usual end clamps 2 and 2^a, center ring 3 and center clips 4 for securing the plates P on the cylinder. The printing plates P are provided with outwardly projecting straight ledges 5 on their straight sides. These ledges are designed to cooperate with T-shaped margin bars 6 and 7, two of which are shown. Each clamping mechanism embodies two of these margin bars in the preferred form. These margin bars are located in a longitudinal slot 8 in the cylinder 1, there being preferably such a slot diametrically opposite the one shown and a second complete clamping mechanism being located therein.

The margin bars 6 and 7 are normally forced to the left as viewed in Fig. 1 by springs 9 and 10 respectively. These springs bear against abutments 11 which are secured to the plate cylinder. The margin bars are adapted to be moved to the right by the use of a connecting rod 12, supplied with jam nuts 13, adjustable connecting link 14, rod 15 and jam nuts 16. On the outside end of the rod 12 a projecting piece 17 is secured by nuts 18 which is moved to the right by either end clamp 2 or 2^a when that clamp is moved back to release the plates.

Means is provided whereby the motion of the end clamps 2 or 2^a to the right for the purpose of releasing them raises the margin bar outwardly in the cylinder, that is, releases them. The contrary motion to the left clamps them down against the ledges of the printing plate. In the form shown this lifting action is provided for by making the bottom edge 20 of each margin bar slanting and by providing corresponding slanting surfaces 21 on outwardly extending projections 22 in the bottom of the slot 8. The locking action is secured by providing correspondingly slanting surfaces 23 and 24 on the bar and the cylinder. It will be seen readily that the motion of these margin bars to the right necessarily forces them upwardly to relieve the ledges 5 on the plates while motion to the left clamps the edges of the plates down.

It is to be understood that the slot 8 is duplicated on the other side of the cylinder, preferably in a diametrical opposite position, and corresponding mechanism is provided on the other side. Thus a cylinder carrying two semi-cylindrical plates is provided with this device for holding down the edges of the plates on both sides of the cylinder. The operator of one end clamp releases or locks up the straight edges of two printing plates.

By this invention means is provided for holding down the straight sides of the printing plate with additional means for releasing the clamping bars in cooperation with clamps on the curved edges of the plate.

It will be understood, of course, that the inclined bevels 20, 21, 23 and 24 do not have to be located in the particular places shown but could be replaced by a similar bevel on the edge of the printing plate. In this case the margin bars would move on a line parallel to the central axis of the cylinder and their under sides which bear on the inclined edge of the plate would be inclined at the same angle.

Although I have illustrated and described only 55

one form of the invention I am aware of the fact that modifications can be made therein by any person skilled in the art without departing from the scope of the invention as expressed in the 5 claims. Therefore, I do not wish to be limited in this respect otherwise than as set forth in the claims, but what I do claim is:

1. The combination with a printing plate cylinder and a movable margin bar having two opposite means along its sides for engaging ledges on two printing plates and provided with surfaces underneath which slant longitudinally, of printing plates on opposite sides of the margin bar having side ledges adapted to be engaged 15 by said means on the margin bar and means whereby, when the margin bar is moved longitudinally on the cylinder, it will be raised or lowered thereby to release or clamp down the straight edges of the plate.
2. The combination with a plate cylinder, of an end plate clamp movable longitudinally of the cylinder, a margin bar between the straight edges of two adjacent printing plates on the cylinder, the margin bar having a longitudinally 20 slanting bottom and side projections having cor-

respondingly slanted upper surfaces, the cylinder having correspondingly slanting surfaces engaging the slanting surfaces on the bar, and means connected with the end clamp for moving the margin bar longitudinally.

3. In a plate clamping device, the combination with means for clamping the curved edges of the plate, of movable means for clamping the straight edges of the plate and means for operating the second named clamping means from the first. 10

4. In a plate clamping device, the combination with an end clamp for clamping the curved edge of the plate, of means for clamping and unclamping the straight edge of the plate, and means for operating the first named means from said 15 clamp.

5. The combination with a plate cylinder and its longitudinal movable margin bar, arranged to clamp and unclamp a plate at its straight edge and a clamp for the curved edge of the plate, of 20 means operated by said clamp for moving said margin bar longitudinally of the cylinder to thereby clamp and unclamp the straight edge of the plate.

HENRY A. WISE WOOD. 25
